UNITED STATES PATENT OFFICE.

HERMAN A. DAVENPORT, OF BROCKTON, MASSACHUSETTS, ASSIGNOR TO UNITED SHOE MACHINERY COMPANY, OF PATERSON, NEW JERSEY, A CORPORATION OF NEW JERSEY.

SOLE-PRESSING MACHINE.

1,163,589.

Specification of Letters Patent. Patented Dec. 7, 1915.

Application filed April 1, 1914. Serial No. 828,687.

To all whom it may concern:

Be it known that I, HERMAN A. DAVENPORT, a citizen of the United States, residing at Brockton, in the county of Plymouth and State of Massachusetts, have invented certain new and useful Improvements in Sole-Pressing Machines; and I do hereby declare the following to be a full, clear, and exact description of the invention, such as will enable others skilled in the art to which it appertains to make and use the same.

The present invention relates to sole pressing machines and more particularly to machines of this type which are employed for laying an outer sole upon a lasted shoe. With the present type of shoe supporting jack employed in this machine the shoe is supported at the toe by a pivoted rest faced with yielding material and curved to approximate the transverse curvature of the shoe. When the shoe is properly jacked this toe rest is seated between the tip of the toe and the instep, but as the size of the shoes operated upon varies constantly, the toe rest must be frequently adjusted to secure this proper positioning of a shoe. The tendency of the last pin is to force the shoe into engagement with the toe post with a pressure sufficient to prevent the proper adjustment of the toe rest when the toe of the shoe is bearing upon the rest. In order to accomplish this adjustment, therefore, it is necessary to remove the toe from engagement with the rest during the relative adjustment of the toe and heel posts, the toe is next allowed to engage with the toe rest, and if not seated properly the operations must then be repeated. It will be obvious to those skilled in the art that this method of jacking the shoe entails more or less time and skill upon the part of the operator.

The object of the present invention is to provide an improved form of shoe supporting jack for a sole pressing machine which supports the shoe firmly during the operation of the machine without causing undue strains in the last and which may be adjusted with facility to position the shoe in the proper relation to the pressing pad without abrading or otherwise injuring the upper.

With this object in view the various features of the invention consist in certain novel features of construction, combina-

tions, and arrangements of parts hereinafter described and claimed, the advantages of which will be obvious to those skilled in the art from the following description.

In the accompanying drawings illustrating the preferred form of the invention; Figure 1 represents an elevation of a portion of a sole laying machine with the present improvements embodied therein; and Fig. 2 is a detail showing an elevation of the toe supporting arm and roll journaled therein.

The illustrated embodiment of the invention is shown in connection with a sole laying machine of the usual type comprising a sectional pressing pad indicated at 1 and a head 2 carrying a heel post 3 and a toe post 5. The heel and toe posts are slidingly supported upon the head 2 in the usual manner and are provided with connections which are actuated by the hand wheel 6 to move the posts toward and from one another. The heel post has a last pin 7 fulcrumed thereon which is normally actuated by a spring 8 to move the shoe into engagement with the toe post. This construction of the shoe supporting jack is well-known in the art and is fully disclosed in patent to Coupal, No. 353,251, dated November 23, 1886.

In the present improved construction the shoe is supported at the toe by a roll which is journaled freely upon the end of the toe post in order that it may roll over the upper of the shoe as the latter is adjusted to position it upon the jack. This roll does not abrade or otherwise damage the upper if moved thereover and furthermore, if the roll is not seated accurately with relation to the shoe it will automatically find the lowest portion of the last when pressure is applied to the shoe. In the simplest and most efficient form of the invention which has yet been devised the roll is provided with a core of comparatively hard material and an outer surface of softer, yielding material to engage with the upper of a shoe. It will be obvious to those skilled in the art that with this construction the entire peripheral surface of the roll is utilized and the wear is distributed uniformly, enabling the roll to be used, for an almost indefinite period. Furthermore, there are no projecting corners or metallic surfaces to engage with and

score or mar the upper as the roll wears. In using the roll in connection with the pressing pad of the usual form it will be noted from an inspection of Fig. 1 that the shank of the pressing pad is provided with raised portions to secure an increased pressure at this point and when pressure is applied to the shoe sole if the shoe is not properly centered with relation to the form the raised portions upon the shank of the pressing pad tend to cause a slight bodily movement of the last and the toe and heel posts to locate the corresponding portions of the pressing pad and shoe sole in proper operative relation to one another.

The toe post 5 is provided with a forked outer end 10 having a shaft 11 secured therein upon which a roll 12 is loosely journaled. This roll is provided with a metallic bushing 14 which surrounds the shaft and forms a bearing for the roll, a core 15 of comparatively hard rubber, and an outer surface layer 16 of soft rubber vulcanized to the core. The outer surface layer is concaved to conform substantially to the transverse curvature of the shoe and with this construction practically a line contact is formed between the roll and shoe. The formation of the roll of hard and soft rubber enables the upper of a shoe to be engaged by a soft yielding surface whereas the hard rubber core furnishes a firm support for the outer layer and serves to securely bind this layer to the metallic bushing.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:—

1. A sole pressing machine, having in combination, a pressing pad and a shoe supporting jack comprising a heel post and a toe post having provision for a relative longitudinal adjustment, and a roll journaled upon the toe post and arranged to engage with and roll over the upper when the shoe is adjusted by the pressure of the pad thereon.

2. A sole pressing machine, having in combination, a pressing pad and a shoe supporting jack comprising a heel post and a toe post, connections between the two posts for simultaneously adjusting them to position the shoe in a predetermined longitudinal relation to the pad, and a roll journaled upon the toe post and arranged to engage with and roll over the lasted upper as the toe post is adjusted during the jacking of the shoe.

3. A sole pressing machine comprising a shoe supporting jack having a toe post, and a roll freely journaled upon the end of the toe post having an inner core of hard rubber to form a support, and an outer concave surface layer of softer rubber to yieldingly contact with the upper of the shoe.

4. A sole pressing machine comprising a shoe supporting jack having a toe post, a metallic bushing freely journaled upon the toe post, a core of hard rubber surrounding the bushing, and an outer surface layer of softer rubber secured to the core and arranged to yieldingly engage with the upper of the shoe.
